UNITED STATES PATENT OFFICE.

WILLIAM Y. FARNSWORTH, OF SEATTLE, WASHINGTON.

VERNIER RHEOSTAT.

Application filed June 28, 1922. Serial No. 571,366.

My invention relates to improvements in rheostats, and more particularly to devices of that character known as vernier rheostats, and which are especially desirable for use in connection with radio receiving and sending apparatus.

In the most common types of rheostats now used in radio sets, the resistance wire is wound about a core; one end of the wire being electrically connected with the circuit, and a blade, which is connected in the circuit, is mounted for adjustment along the coil to contact with the different windings in order that a varying amount of resistance may be thrown in the circuit. It is apparent, however, that in rheostats of this construction, there is a definite number of contact points and hence only a definite number of different amounts of resistance can be obtained, leaving a length of wire between each of the contact points along which adjustment is not possible. The result of this is that, when the contact blade is adjusted along the coil, the resistance jumps from one step to another and it is not possible to obtain an amount of resistance between amounts thus provided for.

It is therefore the object of this invention to provide a vernier rheostat whereby any desired amount of resistance that is possible within the limits of the device may be thrown into the circuit; that is: a rheostat which has an infinite number of contact points.

A further object of the invention resides in the provision of a vernier rheostat whereby the major and vernier adjustment may be made by rotative movement of a single adjusting knob.

Other objects of the invention reside in the provision of pointers whereby the relative positions of the vernier and resistance coil blades may be indicated.

It is also an object of this invention to embody these features of adjustment in a condenser especially useful in radio receiving and sending apparatus.

Other objects of the invention reside in the details of construction of the parts embodied in the device, and in the mode of operation.

In accomplishing these and other objects of the invention, I have provided the improved details of construction, the preferred forms of which are illustrated in the accompanying drawings, wherein—

Figure 1 is a central section of a vernier

rheostat constructed in accordance with the present invention.

Figure 2 is a back view of the same.

Figure 3 is a central, sectional view of a condenser embodying features of construction as used in the rheostat.

Figure 4 is a back, end view of the condenser.

Referring more in detail to the drawings— 65
1 designates what may be an insulating panel, of fibre or bakelite, upon which the rheostat is mounted, and fixed to the inner side of the panel is a circular shell, comprising a base plate 2 and an integral peripheral 70 rim, or flange 3. Fitted within the shell is a circular plate 4 of an insulating material, such as hard rubber, or fibre, and extended through this and the base of the shell are screws 5, as shown in Figure 2, whereby the 75 shell is fixed to the panel.

Fitted against the rim 3 of the shell and extending from the same, is a ring 6 of fibre which, at its inner edge, is fitted between the rim of the shell and edge of the 80 plate 4, and within this ring is fitted a circular, insulating core 7 upon which a resistance wire 8 is wound, in a series of regularly spaced apart convolutions. One end of the resistance wire is fixed to a binding post 9 85 mounted within the shell and to which a circuit wire 10 is connected, while the other end of the wire is fixed in the core.

Mounted coaxially of the shell, is a sleeve 11 which extends rotatably through the 90 panel, the base of the shell and plate 4, and at its inner end it has a collar 12 adjustable thereon that may be fixed at different points of adjustment by means of a set screw 14 threaded through the same, and mounted on this collar is a blade 15 which slidably engages the coils of resistance wire and may be adjusted to different positions along the coil to vary the resistance in the circuit.

Rotatably extended through the sleeve 11 is a shaft 16 provided at the outer side of the panel 1 with a turning knob 17 and at its inner end has a collar 18 adjustable thereon and secured by a set screw 19 at different points of adjustment. Mounted 100 on this collar is a vernier blade 20 which extends beyond the resistance coil and has a downturned end portion 21 that can be moved, by rotation of the knob 17, in rubbing contact along a vernier resistance wire 22 that is wound about the outer face of the insulating ring 6 within a groove pro-

vided therein. One end of the vernier wire is fixed in a binding post 23 mounted within the shell and to which the other circuit wire 24 is connected, while the other end of the wire is fixed in the ring 6, as is shown in Figure 2.

Mounted in the blade 20 is an inwardly extending post 25 which extends through an arcuately formed slot 26 in the major resistance blade 15 so that movement of the latter can be effected by the connection provided through the post and blade 20 with the shaft 16.

In this construction, the slot 26 is of such length and is so located, that a movement of the vernier blade in opposite directions may be made which will cause the end thereof to move along the vernier wire a distance equal to the length of wire in one coil of the resistance wire 8, without causing movement of the major resistance blade. This provision makes possible the varying of the amount of resistance by manipulation of the vernier between the amounts provided for by adjustment of the blade between windings of the coil.

Assuming that the parts are so constructed and assembled, and that circuit wires 10 and 24 are connected with the binding posts 9 and 23, it will be apparent that the circuit will flow from wire 10 along post 9, coil of resistance wire 8, through blade 15, shaft 16, blade 20, vernier wire 22, binding post 23 and then out on circuit wire 24. A desired amount of resistance may be thrown into the circuit by turning the knob 17 to advance the blades along the coil and vernier wires to the approximate point or just slightly beyond the desired point and then turning the vernier blade back to get the exact amount by cutting out part of the vernier wire.

The position of the blades is indicated to the operator by means of pointers 29 and 30 that are fixed respectively to the knob 17 and sleeve 11 at the outside of the panel 1.

It will be seen that in this way the desired amount of resistance may be had by adjustment of the major blade 15 along the coil and that any desired amount between the amounts provided by the coil may be obtained by adjustment of the vernier blade.

It is apparent that various changes in construction of the device may be made without departing from the spirit of the invention, one being in the lost motion connection between the blades. It may be desired to effect movement of the major resistance blade by mounting a pin in the turning shaft and extending this pin through a slot provided in the sleeve on which the major resistance blade is mounted; or by the provision of upturned ears or projections on either member engaged with the other.

In Figures 3 and 4, I have illustrated a

condenser construction which operates in a manner similar to the rheostat just described. In this condenser a vernier adjustment is also provided for by manipulation of the same knob whereby the major adjustment is made.

The condenser comprises a plurality of plates 31 that are supported in parallel, spaced relation from an insulating panel 32, by means of three screw posts 33 which have ends fixed in the panel and which extend through the lower edges of the plates; there being spacers 34 mounted on the screws between the plates to space them equally apart. Also mounted on the screws are insulated posts 35 and 36 wherein a sleeve 37 is revolvably mounted and which extends through the panel 32 and has a pointer 38 fixed thereto. Condenser plates 39 are mounted on the sleeve, to be revolved therewith to different points of adjustment between the plates 31.

A shaft 40 extends revolvably through the sleeve, and this has a turning knob 41 fixed to its outer end, and a condenser plate 42 at its inner end which is adapted to be moved into and from between condenser plates 43 and 44 mounted in alinement with the plates 31 at the inner ends of the screw posts 33.

.Rotative movement of the sleeve 37 is effected by a certain connection with the knob 41; the connection comprising a stud 45 that is fixed within the pointer 38 and which extends within an arcuate slot 46 formed in a pointer plate 47 that is fixed on the inner face of the knob 41. The slot 46 extends through an arc of 180 degrees, which permits adjustment of the plate 42 into and from between the plates 43 and 44 without effecting the adjustment of plates 39.

To obtain a desired adjustment of the condenser, the knob 41 is rotated until the end of slot 46 engages stud 45 and causes rotation of the sleeves 37 whereon the plates 39 are mounted to carry the blades between the plates 31. An approximate capacity may thus be obtained, then by turning back the knob to adjust the plate 42, the exact capacity desired may be obtained.

While I have illustrated a condenser having but one movable vernier plate and two fixed vernier plates, it is apparent that as the capacity of the condenser is changed the number of vernier plates may be changed correspondingly as is necessary.

It is further noted that the arrangement and location of vernier plates with respect to the main condenser and mounting panel may be changed if desirable so that the vernier plates are between the mounting panel and main plates, and the operating connection made by means of a pin fixed in the shaft extending on one side through a slot that may be made in the sleeve.

Having thus described my invention, what I claim as new therein and desire to secure by Letters-Patent, is:

1. A rheostat of the class described, comprising a major resistance coil having a circuit connection at one end, a vernier wire having a circuit connection at one end, a major resistance blade movable in contact with the coil; said blade having a slot therein, a vernier blade movable in contact with the vernier wire and having electrical connection with the major resistance blade, a turning shaft fixed to the vernier blade and a post mounted in the vernier blade and extended through the major blade slot whereby adjustment of the major blade may be effected by turning the shaft, and a vernier adjustment may be made without moving the major resistance blade. 50
2. A rheostat of the class described, a circular shell, an insulating ring mounted within the shell, a resistance coil arranged circularly within the ring, a turning shaft mounted coaxially of the shell, a sleeve 55 revoluble on the shaft, means for electrically connecting one side of an electric circuit with the coil, a vernier wire extended about the ring, means for connecting one end of the vernier wire with the opposite side of the electric circuit, a blade mounted on the turning shaft and having rubbing contact with the vernier wire, a blade mounted on the sleeve having rubbing contact with the resistance coil and having an arcuate slot 60 therein and a post mounted in the vernier blade and extended through said arcuate slot for the purpose set forth. 75
3. A device as in claim 2 wherein pointers are fixed to the turning shaft and to the sleeve whereby the relative positions of the blades may be indicated. 80
4. In a rheostat of the class described, a base provided with a grooved boss and with a recess, a resistance coil housed partially within said recess and fixedly retained on the base, a resistance member housed partly within the groove of said boss and also fixedly retained on the base, a non-slidable spindle limited to rotative movement on the base, a plurality of contact members one of which is fixed to the spindle and the other is idly mounted thereon, said contact members being adapted for electrical contact with the resistance coil and the resistance member, respectively, and a lost motion connection between the two said contact members whereby the members are adapted for conjoint movement with the spindle and one member is shiftable by the spindle independently of the other member. 85
5. A rheostat of the class described, embodying a base provided with an arcuate recess and with a boss concentric to said recess, said boss having a peripheral groove, a resistance coil partly housed within the recess, a resistance member partly housed in the groove of the boss, a non-slidable spindle limited to rotative movement in the base, a contact arm journaled on the spindle, said arm having a recess producing a plurality of shoulders, another contact arm fixed to the spindle, and a stud fixed to the latter arm and positioned to travel within the recess and to abut the shoulders on the other arm. 70
6. A rheostat comprising an insulating base disk, a resistance wire secured to said disk, a main resistance coil having an axis concentric with said wire, an axle pin through said base, a switch arm having a hub fixed on said pin and having an end coacting with said resistance wire, a second switch arm loosely mounted on said pin and coacting with said main resistance coil, means comprising a pin and slot connection operably connecting said switch arms, and an operating knob on said axle pin. 85
